UNITED STATES PATENT OFFICE.

JOSIAH G. WINGER, OF GRAND VALLEY, PENNSYLVANIA.

DESIGN FOR A COMBINED INKSTAND AND PEN-RACK.

SPECIFICATION forming part of Design No. 16,852, dated August 10, 1886.

Application filed June 17, 1886. Serial No. 205,491. Term of patent 7 years.

To all whom it may concern:

Be it known that I, JOSIAH G. WINGER, a citizen of the United States, residing at Grand Valley, in the county of Warren and State of Pennsylvania, have invented and produced a new and original Design for a Combined Inkstand and Pen-Rack, of which the following is a specification, reference being had to the accompanying drawing, forming part thereof, in which I have illustrated my design by a perspective view.

The leading feature of my design is a combined inkstand and pen rack, which represents the mechanical appliances used for oil-wells.

A refers to the tower or derrick, within which is represented the simulation of a pump, B, showing a spout which extends over the simulation of a receiving-tank, C, the piston-rod of the pump being shown as attached to the working-beam D. The crank-shaft of the driving-wheel is shown as having a pitman, e, which is represented as attached to the working-beam D.

E represents a pivoted bar, and f a lever. 25
G represents a covered shed or structure, which extends from the engine-house H to the derrick A.

The ink-well is represented by the tank C. 30
The design is mounted on a platform, I, which is provided at its front end with a depression or recess, J.

I claim—

The design for a combined inkstand and pen-rack herein shown and described, the 35 same consisting of a miniature representation of an oil-well, representing a derrick, A, pump B, tank C, working-beam D, shed G, and engine house H, the whole being mounted on a platform, I, having the groove J upon its front 40 edge, as shown.

In testimony whereof I affix my signature in presence of two witnesses.

JOSIAH G. WINGER.
